Inventor:

L. Franklin Smith

United States Patent Office.

L. FRANKLIN SMITH, OF PHILADELPHIA, PENNSYLVANIA.

Letters Patent No. 70,758, dated November 12, 1867.

IMPROVEMENT IN LOW-WATER INDICATORS.

The Schedule referred to in these Letters Patent and making part of the same.

TO ALL WHOM IT MAY CONCERN:

Be it known that I, L. FRANKLIN SMITH, of the city and county of Philadelphia, and State of Pennsylvania, have invented a new and useful Improvement in Low-Water Indicators; and I do hereby declare that the following is a full and exact description thereof, reference being had to the accompanying drawings, and to the letters of reference marked thereon.

The nature of my invention mainly consists in the arrangement of a water-gauge and three-way cocks in relation to the boiler, and with reference to an expanding tube, which operates an alarm, as represented in the following description. In the accompanying drawings—

Figure 1 represents a front elevation of the improved apparatus.

Figure 2 is a vertical section of the same at the red line 1 2 of fig. 1.

Like letters in both the figures indicate the same parts.

A is a short pipe, which communicates with the water in the boiler, below the water-line at one end, and at the other end with the T-fitting B, which is connected with the brass expanding-tube C by means of the short pipe D and fitting E. The said tube, by means of its connection with the boiler, as described, is filled with water when the same is above the water-line; but when the surface has descended below the water-line, the water in the tube descends into the boiler, and steam takes its place, and the heat thereof expands the tube and throws the short end of the lever F upwards, the lever having its fulcrum-pin *a* through the cheeks *b b* of the connecting-head *c* of the vertical steel rod G, whose lower end passes through the plate *d* of the fitting E, and is provided with nuts *e e* for adjusting the fulcrum-pin *a*. In the ascent of the short arm of the lever, the long end bearing on the front end of the weighted lever H, whose fulcrum-pin *f* is supported in the cheeks *g* of the arm *h*, on the upper end of the stem I of the whistle J, the vertical rod *i* of the valve K is borne down far enough to open the valve for the escape of the steam to blow the whistle, the steam from the boiler passing up from the base-bowl L; which communicates with the upper part of the boiler by means of the three-way cock M. On the back end of the lever there is a weight, N, which closes the valve. O is a glass tube, which constitutes the water-gauge. Its upper end is confined in the chamber P, and its lower end in the chamber P', which has communication with the water in the boiler by means of its connection with the T-fitting B, through the three-way cock Q, and the passage R, in the series of connecting pipes between said cock and the fitting.

The cock Q answers the double purpose of opening and closing the communication between the boiler and the water-gauge. The three-way cock M answers the double purpose of opening and closing the communication between the whistle and the boiler and the water-gauge, separately and conjointly. The whistle may be used for the common purpose of a call-whistle by attaching a rod or cord to the front end of the lever H. The steel or iron rod G may be placed on either side of the expanding-tube C.

What I claim as my invention, and desire to secure by Letters Patent, is—

1. The arrangement of the water-gauge O, chambers P and P', and three-way cocks M and Q, in relation to the boiler, and with reference to the expanding-tube C and fixed rod G, substantially as described, and for the purposes specified.

2. The arrangement of the weight N, with the lever H and arm *h* for closing the valve K, substantially as described.

In testimony that the above is my invention, I have hereunto set my hand and affixed my seal this 25th day of February, 1867.

L. FRANKLIN SMITH. [L. S.]
